CLAIM

I claim the ornamental design for a bottle, as shown and described.

DESCRIPTION

FIG. 1 is a front perspective view of a bottle showing my design;

FIG. 2 is a front view of the bottle shown in FIG. 1;

FIG. 3 is a side view of the bottle of FIG. 1, the opposing side being identical; and,

FIG. 4 is a top view of the bottle of FIG. 1.

1 Claim, 4 Drawing Sheets

FIG. 1

FIG. 2

FIG. 3

FIG. 4
